UNITED STATES PATENT OFFICE.

CHARLES F. BURKHART, OF BUFFALO, NEW YORK, ASSIGNOR, BY MESNE ASSIGNMENTS, TO BURKHART CORPORATION, OF BUFFALO, NEW YORK, A CORPORATION OF NEW YORK.

SHOE-POLISHING MACHINE.

1,181,834.

Specification of Letters Patent.

Patented May 2, 1916.

Application filed September 19, 1906, Serial No. 335,310. Renewed December 21, 1915. Serial No. 68,100.

To all whom it may concern:

Be it known that I, CHARLES F. BURKHART, a citizen of the United States, residing at Buffalo, in the county of Erie and State of New York, have invented certain new and useful Improvements in Shoe-Polishing Machines; and I do hereby declare the following to be a full, clear, and exact description of the invention, such as will enable others skilled in the art to which it appertains to make and use the same.

This invention relates to improvements in shoe polishing machines, and particularly to such as are entirely automatic in operation.

The invention comprises certain novel constructions, combinations and arrangements of parts as will be hereinafter fully described and particularly pointed out in the claims.

From the present application, application Serial Number 365294 has been divided and filed March 29, 1907, limited to the blacking delivering means herein illustrated and described to limited extent.

In the accompanying drawings:—Figure 1 is a longitudinal, vertical section taken on the plane indicated by line 1—1 of Fig. 6, and the main carriage being indicated as nearing the terminus of its first forward stroke. Fig. 2 is a longitudinal, vertical section taken on the plane indicated by line 2—2 of Fig. 5, the main carriage drive being omitted for the sake of clearness, the main carriage being illustrated in its rear-most position. Fig. 3 is a similar view taken on the same plane, the same parts being omitted, the main carriage being indicated in the position immediately after starting on its fourth rearward stroke. Fig.

4 is an enlarged, detail, fragmentary view, partly in section and partly in elevation, indicating the heel carriage, lock and operating parts. Fig. 5 is a longitudinal, horizontal section taken on the plane indicated by line 5—5 of Fig. 2. Fig. 6 is a transverse, vertical section taken on the plane indicated by line 6—6 of Fig. 2, the parts being shown on an enlarged scale, and parts being omitted for the sake of clearness. Fig. 7 is a transverse, vertical section taken on the plane indicated by line 7—7 of Fig. 2. Fig. 8 is a fragmentary, vertical section taken on the plane indicated by line 8—8 of Fig. 6,

the main carriage driving mechanism being fully shown. Fig. 9 is an enlarged, detail, fragmentary sectional view of the connection between the main carriage and the driving sprocket chain therefor. Fig. 10 is a horizontal section taken on the plane indicated by line 10—10 of Fig. 8. Fig. 11 is an enlarged, fragmentary, sectional plan view of the main reciprocating carriage, the section being taken on the planes indicated by line 11—11 of Fig. 2. Fig. 12, is a fragmentary, vertical section taken on the plane indicated by line 12—12 of Fig. 11. Fig. 13 is an enlarged, detail, fragmentary, sectional plan view of the main reciprocating carriage. Fig. 14 is an enlarged, detail, transverse, vertical section taken on the plane indicated by line 14—14 of Fig. 13. Fig. 15 is a similar view of a fragment of the parts seen in Fig. 14, the parts being illustrated in the condition of operation. Fig. 16 is a detail, perspective view of a set of swinging arms. Fig. 17 is a transverse, vertical section taken on the plane indicated by line 17—17 of Fig. 5, and illustrates on an enlarged scale the heel brush operating mechanism. Fig. 18, is a detail, horizontal section taken on the plane indicated by line 18—18 of Fig. 7. Fig. 19 is an enlarged, detail, sectional view taken on the plane indicated by line 19—19 of Fig. 11, and illustrating in detail the ratchet operating lever for the blacking spray governing mechanism. Fig. 20 is an edge view of the lower end of the said ratchet lever. Fig. 21 is an enlarged, detail, sectional view, taken on the plane indicated by line 21—21 of Fig. 11, the main brush frame locking lever being seen in detail. Fig. 22 is an enlarged, detail, vertical, central section of one of the sliding blocks for the revolving side brushes. Fig. 23 is a perspective view of said block, the bearing being omitted. Fig. 24 is an enlarged, detail, perspective view of the bearing detached. Fig. 25 is a fragmentary view in front elevation of that part of the main brush carrying frame provided with one set of toe brushes. Fig. 26 is a side elevation of the same. Fig. 27 is a detail, fragmentary end view of the frame seen in Fig. 25, the view being taken from the plane indicated by line 27—27 of Fig. 25. Fig. 28 is a horizontal section taken on the plane indicated

by line 28—28 of Fig. 27. Fig. 29 is an enlarged, detail, central, vertical section of one of the toe brushes taken on the plane indicated by line 29—29 of Fig. 25. Fig. 30 is 5 a view in front elevation of the main toe brush frame. Fig. 31 is a vertical, central section therethrough taken on the plane indicated by line 31—31 of Fig. 30. Fig. 32 is an enlarged, detail, perspective view of 10 one of the swinging bearings detached.

In carrying out the preferred embodiment 15 of the present invention, as will be herein-after specifically pointed out, I contemplate the employment of certain details which 20 may, of course, be largely varied without in any manner deviating from the spirit and scope of the invention or altering the principle in the least, the details being fully set forth for the purpose of enabling a full 25 and comprehensive understanding of all of the features of this invention. With this in mind, it is pointed out that the embodiment of the invention illustrated in the accompanying drawings involves an inclosing 30 casing in which are arranged all of the details of construction, so as to be inaccessible to unauthorized persons. The casing is provided with a suitable aperture for the insertion of the shoe, and any preferred 35 controlling mechanism may be provided for governing the starting of the present improved blacking machine. Within the said casing is arranged a main or toe carriage which is mounted to reciprocate within the 40 casing in front of the inserted shoe, and an auxiliary or heel carriage which is mounted to reciprocate within the casing in the rear of the shoe. A main or toe brush frame is mounted upon the main carriage and arranged 45 to revolve vertically thereon for presenting different brushes to the toe and side portions of the shoe. A heel brush is mounted upon the heel brush frame and is arranged to reciprocate transversely of the 50 longitudinal axis of the shoe, means being provided for causing the heel brush to approach the shoe and recede from the same in proper timed relation to the movement of the main carriage. Suitable devices are 55 provided for supplying highly attenuated blacking to the shoe at the proper time relative to the movement of the main carriage so that the introduced shoe will be brushed, blackened, and polished through the operation 60 of the several coöperating elements arranged within the casing without interruption or aid from the party whose shoe is being polished, all of the parts being entirely automatic in their operation and stopping after the performance of their respective functions without the aid of an attendant, the only requirement for causing the machine to perform its entire functions 65 being the starting of the same. Wherefore it will be observed that the mechanism ar-

ranged within the casing is admirably adapted for being controlled by some form of coin governed mechanism, although this does not constitute any part of the present application.

70 Referring to the drawings by numerals, 1 designates a floor and 2—2 the inclosing walls of the casing which is preferably employed in connection with the present improved shoe polishing machine. Upon the 75 floor 1 are arranged tracks 3—3 spaced apart, as clearly seen in Figs. 7 and 10. A main or toe brush carriage 4 is arranged above and movably supported upon the tracks 3 by suitably grooved rollers 5—5 80 which are journaled in bearing blocks 6 fixed to the carriage. The carriage is arranged within the casing 2 and is formed to reciprocate upon the tracks 3.

85 Power shafts 7 and 8 are arranged parallel to each other within the casing 2 and extend throughout the length thereof. Said power shafts are journaled at their ends in suitable bearing blocks mounted upon the floor 1, and at its rear end the shaft 8 is 90 provided with a set of bearing blocks 9—9 spaced a relatively short distance apart, and a pinion 10 is fixed to the shaft between said bearing blocks 9. The bearing blocks 9 extend above the journal of shaft 8 and 95 form bearings for the journals of a stub shaft carrying a pinion 11 meshing with pinion 10, the said stub shaft being provided with a sprocket wheel 12 about which is passed a driving sprocket chain 13. The 100 chain 13 preferably receives power from an electric motor 14, but, of course, may receive power from any suitable source. A sprocket wheel 15 is carried by the above-mentioned stub shaft in the rear of the 105 sprocket 12 and is engaged by a sprocket chain 15' which is passed about a sprocket 15'' fixed to the shaft 7. Thus it will be observed that when the motor 14 is in operation the shafts 7 and 8 will be continuously 110 driven.

115 As it is necessary, for purposes herein-after specified, to have the carriage 4 reciprocate longitudinally within the casing 2, I provide mechanism for producing this operation, as best seen in Figs. 8, 9 and 10. A bearing stand 16 is secured to and extends upwardly from the floor 1, said stand being hollow, as clearly seen in Fig. 8, and provided with bearing sleeves 17—17 in which 120 is journaled a shaft carrying a worm 18, said shaft being provided with a sprocket wheel 19 connected by a sprocket chain 20 to a suitable sprocket on the shaft 7. The stand 16 is provided with bearing sleeves 125 21—21 above and at right angles to the sleeves 17, and a shaft is journaled in said sleeves 21 and carries a worm gear 22 which meshes with the worm 18. The outer ends 130 of the shaft carrying the worm gear 22 are

provided with sprocket wheels 23—23 connected by sprocket chains 24—24 to sprocket wheels 25—25. Each of the sprocket wheels 25 is fixed to a stub shaft journaled in a bearing stand 26 fixed to and extending upwardly from the floor 1, the two stands 26 being spaced apart so as to leave an open space therebetween, and the inner end of the stub shafts carried by the said stands are 10 provided with sprocket wheels 27. Sprocket chains 28—28 are passed about the sprocket wheels 27 and extend forwardly to and pass about the sprocket wheels 29 carried by stub shafts 30—30 journaled in bearing stands 15 31—31, fixed to and extending upwardly from the floor 1. While I have mentioned sprocket chains and sprocket wheels, it is obvious that any other form of belting may be employed as desired. A bracket 32 depends from the body portion of the carriage 4 and is formed with a vertical slot 33, through which extends a shaft 34. The shaft 34 is preferably provided with a rotatably mounted spool 35 arranged within 20 the slot 33 and provided at its ends with annular flanges which retain the spool in place, the spool serving to largely eliminate friction. As clearly seen in Fig. 9, one of the links of each of the chains 28 is provided 25 with an outwardly projecting pin 36 which is preferably formed integral with the link, but, of course, may be connected with the link in any preferred manner. Each of the pins 36 projects through the contiguous end 30 of the shaft 34, and is firmly secured against removal by a suitable cotter 37 which is passed through the end of the pin projecting beyond the shaft. Thus it will be observed 35 that as the chains 28 travel the shaft 34 must of necessity accompany the same, and the carriage 4 will thus be caused to reciprocate according to the travel of the chains 28, the space between the chains being sufficient to accommodate the bracket 32 and the depending flange of the carriage 4 being cut away or notched at its rear end, as at 38, for permitting the carriage to travel without interfering with the operation of the sprocket chains. It is, of course, obvious that the 40 shaft 34 will rise within the slot 33 as the links carrying pins 36 pass about the sprockets 27, and the shaft 34 will drop within the slot 33 as the links carrying pins 36 pass about the sprockets 29. 45 Near the forward end of the casing 2 the same is provided with an opening 39 through which the shoe to be polished is designed to be introduced, and a foot-rest 40 is arranged beneath and slightly in the rear of the opening 39 for facilitating the retention of the foot in proper relation to the parts of the machine. The foot-rest 40 is supported upon a stand 41 which rises from the floor 1, and as seen in Fig. 13, extends 50 through a longitudinal slot 42 in the car-

riage 4, the stand 41 being relatively thin and the slot therefor being comparatively narrow. It is, of course, obvious that the slot 42 is of a length corresponding to the distance traveled during one movement of 70 the carriage 4. The slot 42 is, as seen in Fig. 13, arranged longitudinally, centrally of the carriage, and, of course, the foot-rest 40 bears the same relation to the carriage. 75

Near the forward end of the carriage and on opposite sides thereof are arranged brushes 43. Only one brush 43 is illustrated at each side, but, of course, it is obvious that any desired number may be provided. Each of said brushes is preferably in the form of 80 a frustum of a cone, but may be cylindrical if preferred, and each is carried by a shaft 44 journaled in a bearing sleeve 45. Each bearing sleeve 45 is formed with laterally projecting trunnions 46 journaled in a sliding block or frame 47, the said frame or block being mounted to slide laterally on guideways 48 formed of or connected with the carriage 4, the carriage being formed with transverse slots 49 for accommodating 90 the blocks 47.

As best seen in Figs. 22 and 23, each of the blocks 47 is formed at each side with longitudinal grooves 50 designed to inclose the guideways 48. Thus the blocks 47 are 95 formed to reciprocate transversely of the carriage 4, and in order to normally maintain the said blocks at the inner extreme of their movement, a spring 51 is interposed between the respective block and a bracket 100 52 secured to the respective side of the carriage 4. Each block 47 is preferably formed with a boss 53 at the point of contact of the spring 51, and a guiding pin 54 is preferably fixed to the bracket 52 and projects 105 toward the boss so as to guide the spring 51 and prevent the same from becoming displaced, the inner end of the spring extending into a recess formed longitudinally in the boss 53. As clearly seen in Fig. 7, each shaft 44 extends below the bearing sleeve 45 and carries at its lower end a beveled gear 55 meshing with a corresponding gear 56. The gears 56 are carried respectively by the power shafts 7 and 8. 110 The gears 56 are, of course, splined on their respective shafts and are caused to travel with the carriage 4 by means of a sleeve 57 surrounding the respective power shaft 115 and connected by an arm 58 with a sleeve 59 surrounding the corresponding shaft 44 above the gear wheel 55. It is to be observed that the sleeve 57 engages the respective gear 56 on one side and the beveled gear 55 engages the opposite side of the gear 56 so that gear 56 must travel with the carriage which supports the respective shaft 44. Thus it will be seen that regardless of the position of shafts 44 with respect 125 to the stationary parts of the mechanism 130

as well as with respect to the carriage, the brushes 43 will be rotated as long as the power shafts are being driven. It is further to be observed that the sleeves 45 permit free lateral oscillation of the shafts 44 so that when the blocks 47 are thrust apart or outwardly and the brushes 45 are swung through arcs of circles struck from the longitudinal axes of the power shaft as centers, the gears 55 will simply walk about the gear 56 and the brushes 43 will swing freely while continuing to rotate.

In the operation of polishing a shoe it is, of course, desirable to first remove any dust or foreign substances, and such is one of the functions of the brushes 43, and the brushes 43 are, therefore, not made of material designed to produce a fine finished polish, and, therefore, it is desirable when finishing polish is being produced on the shoe to have the brushes 43 out of operative relation with respect to the shoe. In order to produce this result, stub shafts 60-60 are journaled vertically in the carriage 4, and at their upper ends carry cams 61-61. The lower ends of the shafts 60 carry star wheels 62, as seen in detail in Fig. 18. Each of the star wheels 62 is provided with four points adapted to be successively engaged by operating pawls 63-63 for rotating the shaft 60. The pawls 63 are pivotally mounted upon brackets 64-64 fixed to the stand 41 of the foot rest 40. Each of the pawls 63 is formed with a flat face 63' adapted to engage the stand 41 for preventing the pawl 63 from swinging rearwardly beyond a position at right angles to the longitudinal axis of the carriage 4. In order to normally maintain the flat faces 63' of the pawls 63 in engagement with the stand 41, suitable springs 65 are arranged to engage the pawls and press the same rearwardly. The springs 65 are preferably formed of a single strip of spring material attached intermediate its length to the stand 41, and having its ends bent into suitable shape for engaging the pawls 63 under spring pressure. On the forward movement of the carriage the star wheels will pass the pawls 63 and cause the same to swing forwardly, the pressure of the spring 65, not being sufficient for producing rotation of the star wheels. It will be observed, however, that as the carriage 4 moves rearwardly one of the points of each star wheel 62 will engage the respective pawl 63, which pawl remains immovable during the rearward movement of the carriage so that the star wheel is given a one-quarter rotation. Thus at each reciprocation of the carriage the star wheels will be given one forward step amounting to one-quarter rotation, and, of course, the cams 61 will be correspondingly rotated until, when the final polishing operation is to be performed on the

front portion of the shoe, the longest portion of the cams 61 will engage the sliding blocks 47 and will retain the same in their outermost positions with the brushes 43 out of contact with the shoe.

It is to be observed that the elongated portions of the cam are abrupt so that a single stroke of the star wheel will produce the lateral thrust of the respective block 47 and the next stroke of the star wheel will release the block and permit it to return to its normal, inner position. This insures the operation of the brushes upon the next shoe after the polished shoe has been removed. It is to be noted that the stroke of the star wheels 62 which produces the movement of the cams 61 occasioning the outward thrust of the blocks 47 occurs as the carriage 4 is making its final receding movement, and as the pawls 63 are located approximately centrally of the footrest 40 the brushes 43 will be thrown laterally away from the shoe at a point substantially centrally thereof. The said brushes will be held in this outward position until the carriage 4 makes the first forward stroke of the next polishing operation, the brushes remaining in their outward position until the carriage has moved the full distance forwardly and returned to the point at which the star wheels 62 are again engaged by the pawls 63 and the cams 61 are caused to move out of engagement with the slide blocks 47, so that the brushes 43 will first engage the shoe approximately centrally thereof on the first rearward stroke of the carriage.

Approximately at the rear end of the carriage 4, the same is provided with a vertical standard 66 formed at its upper end with an elongated journal bearing 67 in which is journaled a shaft 68, the upper end of the standard 66 being bifurcated and a sprocket wheel 69 being fixed to the shaft 68 between the arms of the bifurcation. A driving chain 70 connects the sprocket 69 with a sprocket wheel 71 splined on the power shaft 8. The sprocket wheel 71 is caused to travel with carriage 4 by means of brackets 71' depending from the carriage and extending on opposite sides of said sprocket wheel. By preference, each bracket 71' is formed at its outer end with a sleeve slidingly inclosing shaft 8.

The forward end of the bearing 67 terminates in a projecting sleeve bearing 72, upon which is journaled a main or toe brush frame 73. The frame 73, as best seen in Figs. 6, 30 and 31, consists, of a sleeve 74 journaled on the sleeve bearing 72, and provided with forwardly projecting arms 75-75, each provided at its end with a sleeve 76, the sleeves 76 being connected by a rectangular framing 77, which framing is preferably formed integral with the sleeves 76. From the rectangular frame 77 project four sub-

frames 78, each designed to carry one set of toe brushes, as hereinafter fully set forth. Each of the sub-frames 78 consists of a pair of arms 79 formed integral with and projecting laterally from the respective side of the frame 77 and connected by a cross bar 80. Between the frame 77 and the cross bar 80, the arms 79 are formed with alined bearing sleeves 81—81. The arm 79 projects a suitable distance beyond the cross bar 80 and each of said arms is bifurcated and formed into branches 82—82, the outer end of the branches 82 being provided with alined sleeves 83—83. A finger 84 projects beyond one of the sleeves 83 for purposes hereinafter mentioned.

Each of the sub-frames 78 carries mechanism corresponding in all details to all of the other sub-frames and therefore the description of one set of mechanism will apply to all. The shaft 68 carries at its forward end a bevel gear 85, which meshes with bevel gears 86—86. Each of the sleeves 76 has journaled therein a stub shaft 87, and the said stub shafts carry the bevel gears 86. At the opposite end of each of the stub shafts from that carrying bevel gear 86, the shaft carries a bevel gear 88, which meshes with a similar gear 89, fixed to a shaft 90. The shaft 90 is journaled in the bearings 81—81 and at one end carries a sprocket wheel 91 engaged by sprocket chain 92, for purposes hereinafter mentioned.

A swinging journal bracket 93 is arranged between the arms 79 and is formed with a pair of arms having their contiguous ends formed integral with a bearing sleeve 93' and being formed with bearing sleeves 94—94 at their outer ends. The bearing sleeves 94 surround the shaft 90 and support the bearing bracket 93 in position while leaving the same free to swing upon the shaft 90, the arc struck by the outer end of the said bracket in its movement having as its center the longitudinal axis of the shaft 90. A bevel gear 95 meshes with the gear 89 and is fixed to a shaft 96 which is journaled in the bearing sleeve 93'. To the outer end of the shaft 96 is fixed a brush 97, which is preferably in the form of a frustum of a cone. It is to be noted from Fig. 31 and Figs. 2 and 3, that the cross bar 80 has its central portion curved or bent forwardly so as to permit the sleeve 93' to swing forwardly for a short distance, the sleeve being free to swing rearwardly. Each cross bar 80 is preferably provided with a set screw 98 which is designed to be adjusted for limiting the forward movement of the sleeve 93'. A coil spring 99 surrounds the shaft 90 at one side of one of the sleeves 94, and has one of its ends connected with said sleeve, the opposite end of the spring being connected with the sleeve 81 whereby, while the bearing bracket 93 is free to swing away from the bar 80,

the spring 99 will produce a return movement as soon as the bracket is free to return.

A shaft 100 is journaled in one set of the sleeves 83, and a shaft 101 is fixed in the other set of sleeves 83. A sprocket wheel 102 is fixed on the shaft 100 and is engaged by the chain 92 for rotating the said shaft 100, the shaft also carrying a fixed sprocket wheel 103 engaged by a sprocket chain 104 which extends to and engages a sprocket wheel 105 fixed to a shaft 106. The shaft 106 is journaled in bearing sleeves 107—107, one of said sleeves being carried by an arm 108, supported by a sleeve 109, journaled on the shaft 100. The other sleeve 107 is fixed to the arm 110 carried by a sleeve 111 journaled on shaft 101. A spring 112 engages the sleeve 111 at one end and at its opposite end engages one of the sleeves 83.

The arms 79 when in operation are disposed vertically and the arms 108 and 110 project at a forward incline therefrom, as clearly seen in full lines in Fig. 1, and in dotted lines in Figs. 2, 3 and 8. The relation of the parts is also seen in detail in Figs. 25 and 26. The sleeve 109 is provided with a laterally projecting finger 113 which extends in the rear of the contiguous arm 82, and a set screw 114 is threaded through the said arm 82 and is adapted to be engaged by the finger 113, the set screw being adjusted for varying the distance to which the arm 108 may move downwardly, and thus controlling the downward movement of the shaft 106 and the brush 115 carried thereby. The brush 115, and the connected parts are free to swing upwardly and rearwardly, but are designed to be returned to their normal position by the spring 112 when released. The brush 115 is fixed to the shaft 106 midway of its end and the said brush is preferably spool shaped so as to conform to the contour of the toe of the shoe as the brush passes over the same.

From the foregoing, it will be observed that the sprocket chain 70 conveys movement to the shaft 68 and from thence to the several sets of brushes carried by the main or toe brush frame, so that all of the brushes carried by the said frame will be rotated while the parts are in operation. By the use of the bevel gears 89 and 95 and the journal bracket which retains the same in opposite relation, the vertical brush is free to swing vertically transversely of the frame, the horizontally disposed brush 115 being free to accompany the vertically disposed brush 97 and being further free to move upwardly and rearwardly.

As clearly seen in Figs. 1 and 6, the finger 84 of each sub-frame is adapted to contact with the upper end of a lever 116, which lever is pivotally mounted on the carriage 4 and has its lower end extending to a point 130

contiguous to the floor 1. At the lower end of said lever, the same is provided, as clearly shown in Fig. 21, with a pivotally connected bifurcated trip finger 117. The 5 said finger is pivoted at its bifurcated end so that as the carriage travels forward, the finger will ride over a stop 118 fixed to the floor 1 and arranged in the path of the movement of the finger. On the return 10 movement of the carriage, the finger will not be capable of riding over the stop, but will cause the lever 116 to swing upon its pivot and release its engagement with the finger 84, so that the frame 73 is free to 15 revolve. The driving of the shaft 68 has a natural tendency to revolve the frame 73 owing to the friction of the parts driven by the gears 86 and the said parts will be positively driven only when the frame is 20 retained against revolving. Thus when the stop lever 116 is moved out of the path of movement of the finger 84, the main frame 73 will begin to revolve, but as the lever 116 moves quickly past its stop 118, it will 25 swing back to its normal position almost instantly and thus be in a position to interrupt the movement of the main frame as soon as the finger 84 of the next sub-frame arrives at the position whereat the former 30 finger was released. Thus it will be seen that with each rearward stroke of the carriage 4, the main brush frame 73 will be permitted to make a one-quarter revolution, or in other words, will be permitted to travel 35 the distance necessary for presenting a new sub-frame with its mechanism at the point occupied by the preceding sub-frame. The lever 116 and the finger 84 are, of course, disposed in such relation to the foot rest 40 that, at each operation, the main brush frame is stopped in its rotation at the proper point for causing the particular set of brushes accompanying the given finger 84, to be positioned in the same longitudinal planes of the machine as those occupied by the foot rest, so that as the carriage 45 approaches the foot rest, the brushes to be in a position for operating upon a shoe thereon.

50 By preference, the brushes 97 and 115 carried by one of the sub-frames are of relatively coarse material and serve to aid in removing any dust or foreign substances from the shoe. The set of brushes of the 55 next sub-frame are of finer material and serve to dry the shoe after the application of blacking, as hereinafter described. The brushes of the third sub-frame are still finer and polish the shoe to some extent.

60 The fourth sub-frame carries brushes which are preferably made of cotton flannel or other material especially designed to put a finishing polish on the shoe, and, as will be hereinafter pointed out, when the brushes 65 of the last sub-frame are operating upon

the shoe, the laterally disposed brushes 43 will engage the shoe only during the forward stroke of the carriage and a portion of its rearward stroke, the brushes being thrown outwardly at a point approximately 70 centrally of the shoe on the last receding stroke of the carriage by means of the cams 61.

After the first stroke of the carriage 4 has been completed and all the foreign substance removed from the shoe, it is necessary to supply blacking to the shoe prior to the operation of the drying brushes and, in order to accomplish this result, I provide mechanism seen in detail in Figs. 10 80 to 15 inclusive, and Figs. 19 and 20. Liquid blacking is employed and the supply thereof is carried in tanks 119—119 arranged upon the carriage 4 on opposite sides of the slot 42. Mounted upon each tank 119 is 85 a bracket 120 which extends upwardly from the tank and is provided with laterally projecting pairs of parallel fingers 121. A tube 122 rises from the respective tank 119 beneath each set of fingers 121, and a rod 123 is passed through each set of fingers 121 and is vertically movably supported thereby in axial alignment with the respective tube 122. The upper end of each bar 123 is provided with a weight 124 which 90 normally maintains the lower end of the bar in engagement with the upper end of the tube 122 for closing the same. If preferred, the tube 122 may have its upper end restricted, as at 125, and the rod 123 95 may be provided with a reduced portion 126 designed to enter the restricted upper end of the respective tube for closing the same. The pin 126, of course, prevents the restricted portion of the tube 122 from remaining clogged, and the diminishing of the diameter of the tube produces a fine vaporous discharge when a partial vacuum is produced in the tube by the passing of a current of air above the tube, as will be hereinafter fully described. As many of the tubes 122 may be provided for each 100 of the tanks 119 as are found desirable.

The rods 123 carried by the fingers 121 must, of course, be elevated in order to permit discharge from the pipes 122, and said rods will normally remain upon said tubes by reason of the weight 124, and therefore the rods constituting a set carried by each tank 119, are connected by a connecting bar 127. In order to produce a distribution of blacking over the entire area of the shoe, the tubes 122 are formed of different lengths so as to deliver blacking at various elevations, and for this reason, the several sets of fingers 121 are at different heights and therefore the connecting bar 127 is of necessity shaped into the form of steps. The bar 127 is preferably formed integral 115 with an operating rod 128, which extends 120

downwardly from the bar 127 at a suitable point intermediate the length thereof, the rod 128 being bent at an angle intermediate its length producing a bend or abutting portion 129, that portion of said rod which extends beyond the bend extending downwardly and being provided at its lower end with a valve 130 positioned above and adapted normally to close an aperture 131 in the top or cover of the respective tank 119. The aperture 131 will, of course, be open when the shoulder 129 is elevated, so that air will be admitted to the tank 119 for permitting of the removal of blacking 15 from the tank without the production of a vacuum therein. In this connection, it is observed that the tube 122 extends preferably to a point near the bottom of the respective tank 119 so as to insure the removal 20 of substantially all of the blacking from the tank through the tube.

Each of the brackets 120 is provided with a bearing 132 in which is journaled a crank shaft 133 engaged at one end by a crank arm 134 whose wrist pin 135 is engaged by a link 136. The opposite end of the crank shaft 133 carries a crank arm 137 which extends beneath the shoulder 129 in position for elevating the bar 128 and connected parts when the crank arm 134 is swung downwardly and rearwardly by a rearward thrust of the link 136. At its rear end, the link 136 pivotally engages an operating lever 138 pivoted, as at 139, to a bracket 140 rising from the carriage 4.

It will be noted that the mechanisms connected with the two tanks 119 are exact duplicates of each other and have therefore been so described. It is to be observed that 40 there are two brackets 140 which are suitably spaced apart upon the carriage 4 and are provided with journal bearings for the journal end of the actuating shaft 141. The shaft 141 carries at each end a cam wheel 142, each of said cam wheels being provided with two cam projections 143 adapted as the cam wheels are rotated to contact with the respective levers 138. The cam projections 143 engage the lower ends 50 of the levers 138 and by forcing the same forward, draw rearwardly the upper ends thereof and produce a rearward thrust of the links 136 with the resultant opening of the apertures 131 and the elevation of the rods 123 for opening the tubes 122.

As above described, the main brush frame is provided with four sub-frames each carrying a set of brushes, and it is of course, obvious that one complete operation upon the 60 shoe will involve an operation of each set of brushes and therefore it will be necessary that the carriage 4 shall have four complete reciprocations during the blacking and polishing of a shoe, and as it is necessary to supply blacking during the course of the opera-

tion, I provide means for actuating the shaft 141 in timed relation to the movement of the carriage such that one of the cam projections 143 will strike the respective lever 138 after the operation of the first set of brushes 70 and prior to the operation of the second set. To obtain this result, I provide a ratchet wheel 144 which is fixed to the shaft 141 and is engaged by a pawl 145 pivotally carried by an actuating lever 146, which is fulcrumed on shaft 141, and seen in detail in Fig. 19. The lower end of the lever 146 pivotally carries a bifurcated trip finger 147, the finger being pivoted in such manner that it is free to swing forwardly away from the 80 lever 146, but cannot swing past the lever 146 in a rearward direction. In the path of movement of the trip finger 147 I have interposed stops 148, so that as the carriage 4 moves forwardly, the finger 147 in riding 85 over the said stops will impart movement to the ratchet wheel 147, one step being imparted to the ratchet wheel each time the finger 147 moves forwardly over a stop 148. Upon the rearward stroke of the carriage, 90 the finger 147 swings upwardly upon its pivot away from the lever 146 and does not actuate said lever. The ratchet wheel 147 is provided with sixteen teeth so as to be given a complete revolution upon the completion of eight reciprocations of the carriage 4, each forward movement of the carriage resulting in the impartation of two steps to the wheel 144 and each rearward movement failing to impart any motion to 100 the wheel 144. Thus it will be observed that upon the fourth forward movement of the carriage 4, counting from the forward movement of the carriage at which one of the cam projections 143 engaged the respective 105 levers 138, the finger 147 will actuate the lever 146 for moving the ratchet wheel 144 in position for causing the levers 148 to be actuated and the rods 136 to be drawn rearwardly. The parts will remain in this position while the carriage moves forwardly until the lever 146 rises at the second stop 148; whereupon the ratchet wheel 144 will be given another step and the cam projections 143 will be moved out of engagement with 115 the levers 148. Thus it is to be observed that by the proper positioning of the parts, the blacking tubes 122 will be opened upon the second stroke of the carriage of each complete blacking and polishing operation and 120 the said tubes will be left open for that portion of the stroke of the carriage during which the tubes are immediately opposite the shoe being operated upon.

In order to insure the delivery of blacking, 125 an air blast tube 149 is arranged immediately opposite each of the tubes 122 and is provided with a horizontally disposed nozzle 150 directing the discharge across the upper end of the respective tube 122, the direction 130

of discharge being toward the shoe being operated upon. The tubes 149 are left open at all times, and therefore when the blacking tubes are closed serve to remove dust and 5 to aid in drying the blacking applied. However, to insure the removal of the dust before the drying and blacking operation, an additional air blast tube 151 may be provided for each set of blacking tubes and 10 preferably disposed in the rear thereof. The tubes 149 of each set, and the tube 151 of the corresponding set extend to a supply pipe 152. Each of the pipes 152 extend from a tank 153 mounted upon the carriage 15 4 preferably at the rear thereof. In order to supply air under pressure to the tank 153, I preferably mount a rotary pump 154 upon the carriage 4 near the said tank and connect the same to the tank by means of a pipe 20 20 155. The pump 154 may be of any ordinary and well known type and is driven by a sprocket chain 156 which extends to and is passed about an operating sprocket wheel 157 splined on the shaft 8, and caused to 25 travel with the carriage 4 by means of brackets 158-158 which depend from the carriage 4 from opposite sides of the sprocket wheel.

In order that the inclosing casing 2 may be made as small as is reasonably possible, 30 the forward wall of said casing is preferably provided with any suitable brackets 159-159 disposed for engaging anti-friction rollers 160 on the shafts 106 of the brushes 115. As the main brush frame approaches 35 the front of the casing 2, the said brackets 159 will, of course, prevent the brushes from striking against the front wall of the inclosing casing and will cause the arms supporting the brushes to swing rearwardly for 40 accommodating the further forward movement of the main brush frame, as shown in Figs. 1, 2 and 3.

Arranged in the front of the casing 2, which, of course, is in the rear of the shoe resting upon the foot rest 40, is arranged an auxiliary carriage 161, seen in Figs. 1, 2, 3, 4, 5 and 17. The carriage 161 is movably mounted upon tracks 3-3 by means of the grooved carrier wheels 162-162, the carriage 161 being designed to reciprocate on said tracks in a manner similar to the movement of the carriage 4.

Projecting laterally from the sides of two of the roller brackets 6 of carriage 161 are studs 55 163 to which are attached ropes 164-164, one rope being arranged on each side of the casing 2. The ropes 164 pass about suitable guiding pulleys 165 to the rear of the casing 2 and then pass upwardly about an elevated pulley 165'. Just beyond the pulley 165', each of the cables 164 carries a weight 166, said weight 166 serving to normally pull the carriage 161 rearwardly.

Secured to the floor 1, in the front portion 60 65 of the casing 2 are suitable journal blocks

167, in which is journaled a shaft 168. The forward end of the shaft 168 fixedly carries a cam wheel 169, provided with four cam grooves 170, and the rear of the shaft 160 is provided with a locking pin or finger 171 70 projecting radially from the shaft. The carriage 161 is provided at its front end with a depending pivotal pawl 172 formed with a flat bearing surface 173, which prevents the pawl 172 from swinging upon its pivot in a 75 rearward direction, but leaves the pawl free to swing forwardly. The pawl 172 is positioned for having its lower end enter the rear end of one of the cam grooves 170 at each forward stroke of the carriage 161, and 80 as the carriage moves forwardly to the extreme of its forward movement, the cam wheel 169 will be given a one-quarter rotation, the pitch of the groove 170 being such as to impart a one-quarter rotation to the 85 cam wheel during the travel of the pawl 172 from one end of a cam groove to the other. On the return stroke of the carriage, the pawl 172 swings forwardly and rides over the cam wheel 169 without effecting the same. 90 The carriage 161 is provided with a locking bar 174 which depends below the carriage and in position for engaging the locking finger 171 when said finger is in the upper position. It is to be observed that as the cam wheel 169 is given a one-quarter rotation at each forward stroke of the carriage 170, the finger 171 will be positioned upwardly once every four strokes of the carriage. The carriage 161 in operation is designed to be struck by the forward end of the carriage 4 just prior to the termination of the first forward stroke of said carriage 4. Of course, the carriage 161 will be caused to travel forwardly with the carriage 4, and as the normal, at rest, position of the carriage 161 is that seen in Fig. 4, the forward stroke of the carriage 161, will cause a one-quarter rotation of the cam wheel 169 which will remove the locking finger 171 from the path of movement of the locking bar 174, and the carriage 161 would then be free to follow the carriage 4 as the carriage 4 recedes, the weights 166 acting to draw the carriage 161 rearwardly. On the next forward stroke of the carriage 4, the carriage 161 will be forced forwardly until the wheel 169 has been given a one-quarter rotation and then the carriage 161 will again follow carriage 4 as the same recedes. This operation continues until carriage 4 makes its fourth stroke, whereupon carriage 161 will be forced forwardly until the wheel 169 is given the one-quarter rotation which brings the locking finger 171 into the path of movement of the locking bar 174, so that as the carriage 4 recedes on its final stroke, the carriage 161 will follow the same but a very short distance and will then remain at its at 100 rest position until the carriage 4 makes the 105 110 115 120 125 130

first stroke of the next operation. It is thus to be observed that the heel carriage or carriage 161 only makes three full reciprocations during one complete operation, the 5 fourth reciprocation being the movement from a locked position forwardly for removing the locking finger 171 from the path of the bar 174, this partial stroke having its complementary part in the stroke required to 10 position the finger 171 in the path of the bar 174.

A standard 175 rises from the carriage 161 at one side thereof and is bifurcated at its upper end, each arm of the bifurcation 15 being formed with a bearing sleeve 175'. A crank shaft 176 is journaled in the sleeves 175' and is provided with a sprocket wheel 177 between the sleeves, which sprocket wheel is engaged by a sprocket chain 178 extending 20 to and passed about a sprocket wheel 179 splined on the shaft 8. The wheel 179 is caused to travel with the carriage 161 by means of a bracket 180 fixed to the carriage and bifurcated at its lower end, the 25 arm of the bifurcation extending on opposite sides of the sprocket wheel. By preference said arms are provided with sleeves slidingly surrounding the shaft 8. The rear end of the shaft 176 is provided with a crank arm 30 181 whose wrist pin engages a pitman 182. The pitman 182 in turn engages a cross head 183 slidingly mounted in horizontal guides 184-184. The cross head 183 preferably consists simply of a plate fitted within the 35 grooves formed in the bars constituting the guides 184-184. Said guides 184 are connected at their ends by vertical bars 185-185, the bars 185 being disposed in the front of the slide or cross head 180 so as to 40 leave the same free to complete a stroke equal to the diameter of a circle described by the center of the wrist pin of the crank arm 181. To the rear face of the slide 180 is fixed a brush 186 which is positioned for engaging 45 the rear end of the shoe mounted upon the foot rest 40.

It will be observed that the brush 186 is reciprocated as long as the shaft 8 is being rotated, and therefore said brush 186 will 50 operate upon the rear end of the shoe whenever the carriage approaches the shoe to a sufficient extent to permit the brush to contact therewith.

The motor 14 may be supplied with current 55 in any desired manner and the current may be controlled by a switch arranged to be operated, for instance, by a coin governed apparatus, or in any other desired manner. When it is desired to polish the shoe, the shoe is introduced in the opening 39 and positioned upon the rest 40 and the circuit for the motor 14 is closed. The carriage 4 immediately begins its advance toward the shoe on the rest 40 and continues 60 its forward travel until the brush 115 rides

up over the top of the shoe and the brush 97 operates on the end of the toe, the brushes 43 operating upon the sides of the shoe as the carriage moves forwardly. Thus the shoe is thoroughly cleaned and prepared for 70 the reception of the blacking. At the extreme rear of the shoe there will be an area of a fraction of an inch which has not been engaged by the brushes 43, but this too is thoroughly cleaned by the brush 186 when 75 the carriage 4 recedes after its first forward stroke. As heretofore pointed out, the carriage 4 upon its first forward stroke presses the carriage 161 forwardly until the wheel 169 is rotated to a sufficient extent for permitting the rearward travel of the carriage 161. Therefore, as the carriage 4 recedes after its first forward stroke, the carriage 161 will follow the same and the brush 186 will effectually clean the extreme rear of the 80 shoe. The carriage 4, after arriving at the extreme of its rearward stroke, of course, immediately begins its second forward stroke, but in the meantime it is to be observed that as the carriage 4 traveled rearwardly after the first forward stroke, the finger 117 of lever 116 will have engaged the stop 118 and released the finger 84. Therefore, as the carriage 4 travels rearwardly upon its first stroke, the main or toe brush 90 frame will be left free to rotate with the shaft 68. Of course, the lever 116 returns to a position in the path of movement of the fingers 84 as soon as the finger 117 has passed over the stop 118, so that the main or 95 toe brush frame is permitted to revolve through only one-fourth of a circle, or until the second sub-frame arrives in the position formerly occupied by the first, so that the second set of brushes of the main toe brush 100 frame is in position for operating upon the shoe disposed on the rest 40 when the carriage 4 arrives at the termination of its rearward movement after the first forward stroke. As the carriage 4 approaches the 105 shoe on its second forward stroke, the blacking will be delivered by the mechanism heretofore described and the spray of blacking will continue until the blacking delivering mechanism has passed from one end of the 110 shoe to the other end thereof; whereupon the supply of blacking will be cut off.

The second set of brushes on the main toe brush frame will engage the shoe as the carriage 4 continues its forward movement and 115 will dry the blacking which has been applied thereto, the brushes 43 serving to dry the blacking as the carriage 4 recedes after its second forward stroke. Upon the return movement of the carriage 4, after the second 120 forward stroke, the main or toe brush frame is again released by operation of the lever 116 and the third sub-frame moves into position opposite the shoe. The carriage 161, of course, follows the carriage 4, and the brush 125 130

- 186 acts upon the rear end of the shoe as the carriage 4 arrives at the extreme of its rearward movement. The carriage 4 then advances on its third forward stroke, the brushes 43 acting upon the sides of the shoe for polishing the same as the carriage 4 advances on the said third stroke.
- 10 The third set of brushes on the toe brush frame engage the shoe and polish the front thereof and the carriage then recedes after its third stroke. As the carriage 4 recedes on its third stroke, the toe brush frame is again released by the operation of the lever 116, and the last set of brushes is brought 15 into alinement. The brushes of the last set are preferably, as above suggested, made of comparatively fine material for producing a finishing polish, and the spool shape of the brush 115, will permit the said brush to act 20 upon a comparatively large area of the front portion of the shoe so that the front portion of the shoe is given a very high polish as the carriage 4 completes its fourth forward stroke. The sides of the shoe toward 25 the rear and the extreme rear of the shoe will not be given quite as high a polish, but will be polished sufficiently by the action of the brushes 43 and the brush 186, the brushes 43 being thrown out of action at a point 30 approximately centrally of the shoe on the last receding stroke of the carriage 4. As the carriage 4 completes its fourth forward stroke, the wheel 169 will be given the final movement for throwing the finger 171 into 35 the path of the locking bar 174, and therefore the carriage 161 will not follow carriage 4 upon the return movement after the fourth forward stroke. As the carriage 4 returns after the fourth forward stroke, the 40 lever 116 is again operated for releasing the main or toe brush frame and the said frame is therefore permitted to revolve with the shaft 68 until the first set of brushes is again brought into alinement with the foot 45 rest 40.
- Any suitable device may be provided for opening the circuit of the motor 14 upon the completion of the return movement of the carriage 4 after its fourth forward stroke. 50 I have not illustrated this feature of construction, as it forms no part of the present application, and as far as the present improved mechanism is concerned, the motor 14 may be controlled by a manually operated switch. It is, of course, obvious that the machine will repeat the above described 55 operation continuously as long as the motor 14 is supplied with current, and all that is required to govern the operation of the present improved polishing machine is the control of the power supply.
- 60 It is to be observed, of course, that while I have disclosed and referred specifically to a number of sprocket chains, any suitable belting may be employed, and I wish it

to be understood that the description and claims are to be construed as covering any belting which may be substituted for that shown and described, and I further wish it understood that the brushes above referred to, may be formed of any material which is found useful in connection with the present improved mechanism.

Having thus fully described my invention, what I claim as new and desire to secure by Letters Patent is:

1. In a polishing machine, the combination of a rotatably mounted brush carrying frame, means for moving said frame bodily toward and away from the article to be polished, brushes carried by said frame and rotatable independently thereof, and means for revolving the frame in a plane at right angles to the path of bodily movement of the frame.

2. The combination of a rotary frame mounted to move bodily independently of its rotation, polishing means rotatably mounted on said frame a power shaft axially alined with respect to the frame, and means for transmitting independent movement from the power shaft to the polishing means.

3. In a polishing machine, the combination with a revolvably mounted frame, of a plurality of sets of brushes carried thereby, each brush of each set being mounted to swing transversely of the frame, a power shaft disposed centrally with respect to the frame, and means for transmitting movement from the power shaft to all of said brushes.

4. In a polishing machine, the combination of a rotatably mounted frame bodily reciprocable in lines parallel to its axis of rotation, swinging brushes carried by the frame, and means for actuating said brushes.

5. In a polishing machine, the combination of a frame having a plurality of pairs of arms, a shaft journaled in each of said pairs of arms, a brush connected with each of said shafts and free to swing thereon, means for rotating said shafts, and means for transmitting movement from each of said shafts to its respective brush.

6. In a polishing machine, the combination of a rotatably mounted frame, a driving shaft arranged in axial alinement therewith, a plurality of sub-frames carried by said rotatably mounted frame, a plurality of shafts carried by said rotatably mounted frame and having their outer ends projecting into the respective sub-frames, polishing brushes carried by said sub-frames, means for imparting movement from the driving shaft to the rotatably mounted shafts, and means for transmitting movement from the last mentioned shafts to said brushes.

7. In a polishing machine, the combination with a rotatably mounted frame having a plurality of sets of arms, a plurality of shafts journaled in said arms, one shaft being arranged for each set of arms, an axially alined power shaft, means for transmitting movement from said power shaft to the shafts carried by said frame, a swinging brush carried between each set of arms of said frame, and means for transmitting movement from the shafts of said rotatably mounted frame to the brushes thereof.

8. In a polishing machine, the combination of a frame formed with a plurality of pairs of arms, a shaft journaled transversely in each pair of arms, a swinging journal bracket supported by each of said shafts, a bearing sleeve carried by each of said journal brackets, a shaft journaled in said sleeve, gears transmitting movement from the transversely arranged shaft to the last mentioned shaft, and a brush carried by the last mentioned shaft.

25 9. In a polishing machine, the combination with a main frame provided with a plurality of sets of arms, a transversely arranged shaft journaled in each set of arms, a swinging journal bracket carried thereby, a shaft journaled in said bracket, means for actuating the transversely arranged shaft, means for transmitting motion from the transversely arranged shaft to the second mentioned shaft, a brush carried by the second mentioned shaft, and means for limiting the degree of swing of the journal bracket.

10. In a polishing machine, the combination with a frame provided with a plurality of sets of arms, a shaft journaled transversely in each set of arms, means for rotating said shaft, a shaft rotatably mounted and supported in position for swinging about the transverse shaft, means for transmitting movement from the transverse shaft to the second mentioned shaft, and a brush carried by the second mentioned shaft.

11. In a polishing machine, the combination of a bodily reciprocable frame, a plurality of shafts journaled therein, means for rotating each of said shafts, a swinging shaft carried by said frame for each of said first mentioned shafts, a support for each swinging shaft, a spring carried by the frame and engaging the support for each of said swinging shafts for limiting the degree of movement thereof in one direction, means for limiting the degree of movement of each swinging shaft in the opposite direction, a brush carried by each swinging shaft, and means for transmitting movement from each of the first mentioned shafts to the respective swinging shaft.

12. In a polishing machine, the combina-

tion of a frame having a plurality of sets of arms, a shaft journaled transversely in each set of arms, means for driving said shaft, a swinging shaft carried by each set of arms, means for transmitting movement from the first mentioned shaft to the swinging shaft, a transverse bar connecting the respective arms of each set and extending in the path of movement of the swinging shaft for limiting the movement thereof, means for limiting the movement of said swinging shaft in an opposite direction, and a brush carried by the swinging shaft.

13. In a polishing machine, the combination with a frame having a plurality of sets of arms, a swinging shaft mounted in each set of arms, a transverse bar for each set of arms extending across the path of movement of the swinging shaft for limiting the degree of movement thereof in one direction, means for imparting movement to said shaft, and a brush carried by said shaft.

14. In a polishing machine, the combination with a frame, a shaft journaled therein, a U-shaped bracket having bearing sleeves at its ends rotatably surrounding said shaft, a bearing sleeve carried by said bracket, a shaft rotatably mounted in said bearing sleeve, means for actuating the second mentioned shaft, and a brush carried by the second mentioned shaft.

15. In a polishing machine, the combination with a frame, of shafts supported by said frame, a pair of arms pivotally engaging said shafts so as to be free to swing laterally with respect to the frame, a lug carried by one of said arms adjacent the pivot and projecting beyond the arm to a point for engaging a portion of the frame, and a brush carried by said arms.

16. In a polishing machine, the combination of a rotatably mounted frame, means for moving the same bodily toward and away from the article to be polished, a plurality of brushes carried by said frame, a driving shaft in axial alinement with respect to said frame, gears for transmitting movement from said driving shaft to said brushes, means normally retaining said frame against rotation, and means for releasing the frame at predetermined intervals whereby the frame may be caused to revolve by reason of the friction between the gears transmitting motion to the brushes.

17. In a polishing machine, the combination of a carriage mounted to move toward and away from the article to be polished, a frame revolubly mounted thereon, a plurality of brushes carried by said frame, a stop lever projecting in the path of movement of portions of the frame and normally remaining in such position, and automatic means adapted for pressing said lever to one side at predetermined intervals for permitting the frame to revolve.

18. In a polishing machine, the combination of an article support, a carriage arranged in front of the article support, an independent carriage arranged in the rear 5 of said article support, means for moving the first mentioned carriage toward and away from said article support, means for causing the second mentioned carriage to follow the first mentioned carriage in its 10 movement away from the support, and means carried by said carriages for polishing said article.

19. In a polishing machine, the combination of an article support, a plurality of 15 carriages adapted to move toward and away from the article support, means for moving one of said carriages toward the article support, the other of said carriages being in a position for being engaged by the former 20 carriage and forced thereby away from the article support, means for returning the second carriage toward the article support after the first carriage has moved away from the same, and polishing apparatus carried by said carriages.

20. In a polishing apparatus, the combination of a longitudinally slotted carriage, a rest for the article to be polished extending through the slot of said carriage, means 30 for reciprocating said carriage, a second carriage normally contacting with the first carriage and adapted to be forced in one direction thereby, means for forcing the second mentioned carriage in the opposite 35 direction, and polishing apparatus carried by said carriages.

21. In a polishing apparatus, the combination of a carriage arranged to move toward and away from the article to be polished, means for moving said carriage, a second carriage adapted to be moved in one direction by engagement of the first mentioned carriage, gravity actuated means for moving the second mentioned carriage in the 45 opposite direction, and polishing apparatus carried by said carriages.

22. In a polishing apparatus, the combination with a reciprocating carriage, means for moving the same, a second carriage 50 adapted to be engaged and moved in one direction by the first mentioned carriage, means for moving the same in the opposite direction, and polishing apparatus carried by said carriages.

23. In a polishing machine, the combination of a reciprocating carriage, means for actuating the same, a second reciprocating carriage arranged to contact with the first mentioned carriage and to be moved in one 60 direction thereby, a cable connected with the second mentioned carriage, a weight engaging said cable for causing the second mentioned carriage to move in the direction opposite to the direction of its movement 65 under the action of the first mentioned car-

riage, and polishing apparatus carried by said carriages.

24. In a polishing machine, the combination with a movable support arranged to move toward and away from the article to be polished, of a plurality of polishing apparatus carried thereby, means for moving the several polishing apparatus successively into position for engaging the article to be polished, a stop for temporarily preventing 70 such movement of the several polishing apparatus, and means for automatically releasing said stop once for each complete movement of the support toward and away from the article to be polished.

25. In a polishing machine, the combination with a movably mounted support adapted to be moved toward and away from the article to be polished, a plurality of polishing devices carried by said support, means 85 for moving said polishing devices successively into position for engaging an article to be polished, and a stop lever disposed for preventing such movement of said polishing devices and means to release the lever for 90 permitting movement of the several polishing devices.

26. In a polishing machine, the combination with a reciprocating carriage, of a plurality of polishing devices arranged thereon, means for moving said polishing devices successively into position for engaging the article to be polished, a lever mounted on said carriage and extending into the path of movement of the said devices and normally preventing movement thereof, and means arranged in the path of movement of the lever for temporarily swinging the lever out of the path of movement of the polishing devices.

27. In a polishing machine, the combination of a reciprocating carriage, polishing devices carried thereby, means for moving said polishing devices successively into position for engaging the article to be polished, a stop lever carried by said carriage and projecting normally into the path of movement of said polishing devices, a stop fixed with respect to said carriage, and a pivoted finger carried by said lever in position for engaging said stop for tripping the lever as the carriage is moved in one direction, the pivotal mounting of the finger permitting the finger to ride over the stop during movement of the carriage in an opposite direction.

28. In a polishing machine, the combination with a support and a power shaft journaled therein, a sleeve journaled about said shaft, a frame supported by and projecting forwardly from said sleeve to a point beyond the end of the shaft, a plurality of journal bearings carried by said frame and having their axes arranged at right angles to the longitudinal axis of the power shaft, a shaft journaled in each 125 130

of said bearings, gears connecting the said last mentioned shafts with said power shaft, brush carrying shafts geared to the second mentioned shafts, and brushes carried by said brush carrying shafts.

29. In a polishing machine, the combination with a movable support and a standard carried thereby, a vertically rotatable frame supported by said standard, a polishing device carried by said frame, a shaft journaled in the standard, means for driving said shaft, and means for transmitting motion from the shaft to the polishing device.

30. In a polishing machine, the combination with a movably mounted carriage, and means for moving the same toward and away from the article to be polished, of a power shaft arranged parallel with the path of movement of the carriage, a shaft journaled upon the carriage, a wheel splined on said power shaft, means for causing said wheel to travel with the carriage, belting connecting said wheel with the shaft on the carriage for imparting movement thereto, polishing devices carried by said carriage, and means for communicating movement from the shaft journaled on the carriage to said polishing devices.

31. In a polishing machine, the combination of a movably mounted carriage, endless belting arranged contiguous to said carriage, means connecting said carriage with said belting; said connecting means being disposed to move transversely of the path of movement of the carriage independently of the carriage, and a polishing device carried by said carriage.

32. In a polishing machine, the combination of endless belting, means for driving the same, a carriage arranged contiguous to said belting, means connecting the carriage to the belting at one point, a guide for said connecting means fixed to the carriage and arranged for permitting said connecting means to move freely transversely of the path of travel of the belting and for preventing movement of the connecting means parallel of the longitudinal travel of the belting, and polishing means carried by said carriage.

33. In a polishing machine, the combination of a horizontally moving carriage, a vertically slotted bracket carried thereby, endless belting arranged contiguous to said carriage, means for driving said belting, a shaft connected to the belting at one point and extending through the slot in said bracket, and a polishing device carried by said carriage.

34. In a polishing machine, the combination of a movably mounted carriage, a pair of endless belts spaced apart and disposed contiguous to said carriage, means for driving said belts, a shaft connecting the belts

at one point and connections between said shaft and carriage for imparting movement from the belts to the carriage, and a polishing device carried by said carriage.

35. In a polishing machine, the combination with a movable carriage, of endless belting arranged contiguous thereto and means for driving said belting, a bracket connected with said carriage and formed with a guideway, a shaft connected with said belting and projecting through said guideway, a spool journaled on said shaft and arranged in the guideway with its flanges extending on opposite sides of said guideway, and polishing means carried by said carriage.

36. In a polishing machine, the combination with a movably mounted carriage, of a pair of endless belts arranged parallel and spaced apart, means for driving said belts, a bracket extending from said carriage between said belts, a shaft connected to both of said belts, a movable connection between said shaft and said bracket, and polishing means carried by said carriage.

37. In a polishing machine, the combination with a movably mounted carriage, of a pair of parallel belts disposed beneath said carriage, means for driving said belts, a vertically slotted bracket depending from said carriage between said belts, a shaft connecting the belts and extending through the slot in said bracket, and polishing means carried by said carriage.

38. In a polishing machine, the combination with a support arranged to move past the article to be polished, a slide movably mounted on said support, a sleeve journaled in said slide, a shaft journaled in the sleeve, and polishing means carried by said shaft.

39. In a polishing machine, the combination with a movably mounted carriage, of a power shaft arranged parallel to the path of the movement of the carriage, a shaft sustained by the carriage and mounted to move transversely thereof, a beveled gear splined on the power shaft, a beveled gear on the lower end of the second mentioned shaft and meshing with the beveled gear on the power shaft, a sleeve surrounding the power shaft on the opposite side of the gear thereof, a sleeve surrounding the second mentioned shaft, a bracket arm connecting said sleeves, and polishing means carried by the upper end of said second mentioned shaft.

40. In a polishing machine, the combination with a support movable past the article to be polished, of a shaft carried thereby and mounted to swing therein, a power shaft arranged to rotate beneath the first mentioned shaft, gears connecting said shafts, the first mentioned shaft being mounted to move through the arc of a circle whose center is the center of said power

- shaft, a spring normally pressing the first mentioned shaft in a direction toward the article to be polished, means for forcing said shaft in an opposite direction, and 5 polishing means carried by said shaft.
41. In a polishing machine, the combination with a support for the article to be polished, of a movable support arranged to move past the article support, a polishing 10 device carried by said movable support and free to move independently of the movable support toward and away from the article to be polished, means for normally pressing the support toward the article to be polished, a cam for moving said support in an opposite direction, means for operating said cam, and means connected with the article support for actuating the said cam operating means.
42. In a polishing machine the combination with a movable support arranged to move past the article to be polished, a polishing device carried thereby and moved independently of the support toward and 15 away from the article to be polished, means pressing said polishing device toward the article to be polished, a cam for forcing the polishing device in an opposite direction, a star wheel connected with said cam, and a 20 pawl engaging said star wheel and fixed with respect to the star wheel, the said pawl being arranged to move freely in one direction, but limited in its movement in the other direction for causing partial rotation 25 of the star wheel at each movement of the movable support past the pawl in the latter direction.
43. In a polishing device, the combination with a carriage movable past the article 30 to be polished, a polishing device carried thereby and arranged to swing freely transversely of the path of movement of the carriage, means for pressing said polishing device normally toward the article to be 35 polished, a cam supported by said carriage adapted to engage said polishing device for moving the same in the direction away from the article to be polished, a shaft carrying 40 said cam extending through the wall of said carriage, a star wheel fixed to the lower end of said shaft, and a pivotally supported pawl retained against movement with respect to the article to be polished and positioned in the path of movement of the 45 points of the star wheel.
44. In a shoe polishing machine, the combination with a foot rest, of a reciprocating carriage arranged to have a portion thereof pass 50 said foot rest, polishing devices carried by that portion of the carriage which passes the foot rest, said polishing devices being movable toward and away from the foot rest independently of the movable carriage, springs for pressing said polishing 55 devices toward the foot rest, cams sustained by the carriage and designed to engage the polishing devices for forcing the same away from the foot rest, star wheels connected with said cams, and pawls carried by the foot rest in position for engaging the star 70 wheels for actuating the cams.
45. In a polishing machine, the combination with a carriage, means for moving the same toward and away from the article to be polished, polishing means carried by said carriage, a rotatably mounted locking device, and means for rotating the same in timed 75 relation to the movement of the carriage for causing the locking device to assume a position in the path of movement of the carriage 80 at predetermined intervals.
46. In a polishing machine, the combination with a carriage, and means for reciprocating the same, of polishing means carried by said carriage, a rotatably mounted locking finger arranged to lock the carriage, when at one point of its rotation, an actuating device for rotating said locking finger with a step by step movement, and means 85 for operating said actuating device in timed relation to the movement of the carriage for imparting movement to the locking finger amounting to a distance of one step for each reciprocation of the carriage.
47. In a polishing machine, the combination with a reciprocating carriage, and polishing means carried thereby, of a bracket depending from said carriage, a locking finger arranged to be introduced into the path of movement of said bracket, and means for actuating said locking finger and moving the same into and out of the path of 90 movement of said bracket.
48. In a polishing machine, the combination with a reciprocating carriage, and polishing means carried thereby, of a rotatably mounted cam, a pivoted finger carried by the carriage in a position for engaging said cam at the completion of each reciprocation of the carriage, and means actuated by the cam 105 for locking said carriage against movement after a predetermined number of reciprocations.
49. In a polishing machine, the combination with a reciprocating carriage, and polishing means carried thereby, of a shaft journaled beneath said carriage, a bracket depending from the carriage, a finger carried by said shaft, a cam connected with the shaft, and means on the carriage arranged to 110 engage the cam for actuating the same and moving said shaft for causing said finger to successively move into and out of the path of movement of said bracket.
50. In a polishing machine, the combination with a reciprocating carriage and polishing means carried thereby, of a rotatably mounted cam wheel provided with a plurality of cam grooves, means connected with the carriage arranged to engage the cam grooves 115 120 125 130

for actuating the cam wheel, and means connected with the cam wheel for locking the said carriage.

51. In a polishing machine, the combination of a reciprocating carriage, a crank shaft journaled thereon, means for driving said crank shaft, a crank arm connected with said crank shaft, a wrist pin connected with said crank arm, a pitman engaging said 10 wrist pin, polishing means supported by said carriage, and means connecting said pitman with said polishing means for imparting movement thereto transverse to the line of movement of the carriage.

15 52. In a polishing machine, the combination of a plurality of carriages arranged to reciprocate toward and away from the article to be polished, one of said carriages being arranged on one side and the other of said 20 carriages being arranged on the opposite side of the article to be polished, transversely reciprocating polishing means carried by one of said carriages, and transversely rotatable polishing means carried by the other 25 of said carriages.

53. In a polishing machine, the combination with a pair of power shafts arranged parallel, of a pair of carriages movably mounted between said power shafts and arranged to reciprocate with their longitudinal axes at all times parallel to said shafts, polishing devices carried by said carriages, and means for transmitting movement from said shafts to said polishing devices.

35 54. In a polishing machine, the combination of a main reciprocating carriage, an independently moving auxiliary carriage, a foot rest interposed between the carriages, means for moving said carriages toward and away 40 from said foot rest, polishing means for the forward part of the shoe carried by the main carriage, and polishing means for the rear part of the shoe carried by said auxiliary carriages.

45 55. In a shoe polishing machine, the combination of a reciprocating carriage arranged to move toward and away from the shoe to be polished, a toe brush frame rotatably carried by said carriage, a plurality of 50 brushes carried by said toe brush frame, means for bringing said brushes successively into operative relation with respect to the shoe to be polished, side brushes carried by said carriage and disposed for engaging the 55 sides of the shoe, and means for at times spreading said side brushes apart and away from the shoe.

56. In a shoe polishing machine, the combination with an inclosing casing, of a carriage arranged therein mounted to reciprocate toward and away from the shoe to be polished, a movably mounted frame carried thereby, a plurality of forwardly inclined supports movably sustained by said frame, 60 polishing devices carried by said supports,

and brackets carried by the forward portion of said inclosing casing and arranged for being engaged by some of said movably mounted supports for retarding the forward movement thereof without interfering with 70 the forward movement of the movably mounted frame.

57. In a polishing machine, the combination with an inclosing casing, of a carriage mounted therein and arranged to reciprocate 75 toward and away from the shoe to be polished, of forwardly extending movably mounted supports carried by said carriage, polishing devices sustained by said supports, and brackets carried by the forward portion of the inclosing casing in position for being engaged by some of said movably mounted supports for retarding the forward movement of the said supports without interfering with the forward movement of the 85 carriage.

58. In a polishing machine, the combination with a revolvably mounted frame, of a plurality of sets of revoluble brushes carried thereby, each brush of each set being 90 mounted to swing transversely of the frame, a power shaft disposed centrally with respect to the frame, and means for transmitting movement from the power shaft to all of said brushes.

95 59. In a polishing machine, a shoe support, a carriage movable toward and from the support, a frame rotatably mounted on the carriage, a latch positioned to engage and maintain the frame against rotary movement, brushes mounted on the frame, means adapted to rotate the brushes, and means actuated by the brush actuating means adapted to release the latch.

60. In a polishing machine, a rotatable 105 frame, a driving gear rotatable concentrically with the frame, a plurality of brushes mounted on the frame and to rotate upon axes removed from the axis of rotation of the frame, and each receiving motion from 110 the driving gear, and means automatically operated to move the frame with a step by step movement.

61. In a polishing machine, a shoe support, a carriage movable toward and from 115 the front of the support, a frame journaled at its center on a longitudinal axis on said carriage, brushes rotatably mounted at the extremes of said frame, means adapted to rotate the brushes, abutments carried at the 120 extremities of the frame, a spring-pressed detent on the carriage positioned to normally engage one of the abutments and maintain the frame against rotation, and automatically actuated means adapted to release the engagement of the detent.

62. The combination of a frame, a shaft journaled upon the frame, a second shaft journaled upon the frame and adapted to swing with the first mentioned shaft as a 130

center, a brush carried by the second mentioned shaft, an arm pivoted to the frame, a horizontal shaft journaled upon the arm, and having its axis of rotation at right angles to the first named shaft, a brush carried by the horizontal shaft, and means to transmit motion from the first mentioned shaft to the horizontal shaft.

63. In a shoe polishing machine the combination of a toe brush having a vertical axis, a top brush having a horizontal axis, spaced swinging side brushes, a relatively stationary heel brush and means to permit independent yielding movement of all of the brushes relative to each other.

64. In a shoe polishing machine, a movable frame, a top brush carried by the frame and provided with a concave periphery smaller at the center, means to permit the top brush to move yieldingly upward, a toe brush carried by the frame and disposed normally within the concavity of the top brush, and means to permit the toe brush to move yieldingly away from the top brush.

65. In a shoe polishing machine, a shoe rest, a main carriage, spaced side brushes mounted on the carriage in mountings adapted to permit the brushes to yieldingly move away from each other, a toe brush mounted on the carriage in mountings

adapted to permit the brush to yieldingly move away from the side brushes, a top brush mounted upon the carriage in mountings adapted to permit the brush to move yieldingly upward, an auxiliary carriage, carrying a brush, and means to produce a concerted movement of the carriages relative to the shoe rest.

66. In a shoe polishing machine, a shoe rest, brushes adapted to move along the sides of the shoe and to have independent rotary motion upon their own axes, a toe brush adapted to engage the toe of the shoe and have independent rotary movement, a top brush adapted to engage the top of the shoe and have independent rotary motion, and means to move and rotate the brushes in timed relation.

67. In a shoe polishing machine, horizontally journaled shafts, a carriage horizontally movable, cleaning and polishing members carried by the carriage and means slideable upon the shafts for transmitting motion to the cleaning and polishing members.

In testimony whereof I affix my signature in presence of two witnesses.

CHARLES F. BURKHART.
